UNITED STATES PATENT OFFICE

2,439,160

ATTENUATOR

Edmund Doucette, Newark, N. J., assignor to The Daven Company, Newark, N. J., a corporation of New Jersey

Application February 26, 1945, Serial No. 579,829

3 Claims. (Cl. 201—55)

1

This invention relates to attenuators as used in the communications field, and more particularly to multiple unit attenuators.

An object of the present invention is to provide an improved construction of multiple unit attenuators which embodies novel features of construction and arrangement of parts resulting in a reduction of the manufacturing costs of the device, a simplification of the construction of multiple unit attenuators, and provides a structure wherein single unit attenuators may be quickly, easily, and inexpensively combined to form multiple unit structures, thereby permitting production manufacture of single unit attenuators or their parts which with slight alterations may be combined into multiple units of any desired degree of multiplication of the single unit.

Another object of the present invention is the provision in multiple unit attenuators of a novel construction of the movable contact operating shafts which permits quick and easy connection of the shafts of single units, making up the multiple unit, for synchronous operation of the shafts and movable contacts, and which further simplifies the assembly of the parts of the attenuator.

A further object of the present invention is to provide an attenuator so constructed and designed as to permit quick and easy inspection, cleaning, or repair of the switch contact members or other internal parts without the need of removing the front unit from its position on an instrument panel, and one which also is dust tight thereby providing improved electrical shielding and further providing protection to the switch rotor and contacts of the front unit of the attenuator.

With these and other objects in view, as may appear from the accompanying specification, the invention consists of various features of construction and combination of parts, which will be first described in connection with the accompanying drawings, showing an attenuator of a preferred form embodying the invention, and the features forming the invention will be specifically pointed out in the claims.

In the drawings:

Figure 1 is a side elevation of a multiple unit attenuator constructed in accordance with the present invention.

Figure 2 is a longitudinal section through the attenuator.

Figure 3 is a cross section taken on the line 3—3 of Figure 2.

Figure 4 is a detail fragmentary section of a part of the attenuator assembly.

2

Figure 5 is a detail cross section taken on the line 5—5 of Figure 2.

Figure 6 is a detail section taken on line 6—6 of Figure 1 showing the manner of fastening together the housings.

Referring more particularly to the drawings, the improved multiple unit attenuator is an adaptation of the single unit attenuator as shown in the co-pending application of John P. Smith, Jr., Serial No. 562,989, filed the 11th day of November, 1944, with some changes and modifications thereto to adapt the single units for connection in a multiple unit.

In the drawings, a multiple unit attenuator is illustrated embodying two single units in combination, but it is to be understood that any number of the single units may be coupled together in the manner of the present invention, as may be desired or required, without departing from the spirit of the present invention.

Each of the single unit attenuators comprises a housing 1 in the form of a cylindrical shell which has the electric current resisting means 2 therein, the stationary contacts 3 being carried by the insulating plate 4. The attenuators each include movable contacts 5 which cooperate with the stationary contacts 3 as is usual in attenuator structures. The movable contact 5 of the unit 1a is carried by an operating shaft 6 which extends axially through the casing 1 and has a turning knob 7 upon its end which projects out of the housing 1. The shaft 6 has a detent gear 8 thereon which is of the same construction as the detent gear shown in the afore-mentioned application of John P. Smith, Jr. The detent gear 8 co-operating with the dished closure plate 9 which is rigidly secured to the housing 1 limits the degree of insertion of the shaft 6 through the electrical resistance mechanism 2 so as to insure proper positioning of the movable contact 5 and of the placing of the proper tension upon the spring fingers 10 of the movable contact when the parts of the attenuator are assembled.

As clearly shown in Figure 2 of the drawings, the shaft 6 extension beyond the collar 11, by means of which the movable contact 5 is attached to the shaft 6, and the portion of the shaft 6 extending inwardly beyond the inner end of the collar 11 is cut away to form a semi-cylindrical section 12, the flat surface 14 of which engages the flat surface 15 of the cut away section 16 of the movable contact operating shaft 17 of the single unit 2a. A guiding and retaining sleeve 18 is mounted about the shaft 17, is pinned thereto, and extends over the cutaway end of the

shaft, the end of the sleeve being flush with the inner end of the cut away portion of the shaft 17 so that when the two units 1a and 2a are assembled in a multiple unit attenuator as shown in section of Figure 2 of the drawings, the two inner engaging flattened ends of the shafts 6 and 17 will be held in proper contact with each other, and the shafts will be connected for synchronous movement which will provide synchronous movement of the movable contacts 5 of the sections 10 1a and 2a.

The housing 1 of the section 2a has its outer end closed by a removable closure cap 19. The open end of which slips over the outer end of the housing 1 as clearly shown in Figure 2, and is held in place by means of a pin 30 which extends through aligning openings 31 in the housing 1 and the closure cap 19. The pin 30 is carried by a flat spring 32, one end of which is secured to the inner surface of the housing 2. A threaded stud 26 is attached to the flat spring 32 intermediate its attached end and the pin 30 and extends through a bayonet slot 25 in the cap 19 and has a nut 20 threaded thereon. When the cover 19 is connected to the housing 1, the nut 20 is threaded outwardly as shown in Figure 6 so as to permit movement of the stud 26 in the bayonet slot 25 to allow the pin 30 to pass through the opening 31 under the spring action of the flat spring 32. After the pin is in place, the nut 20 is tightened against the outer surface of the cover 19 which locks the pin 30 in place and the cover cap 19 on the housing. Upon disconnection of the cover 19 from the housing 1, the nut is threaded outwardly on the stud, and by forcing the nut and stud inwardly the spring 32 will give and move the pin 30 out of the holes 31.

The inner end of housing 1 of the unit 2a is closed by the rigidly attached closure plate 22. The housing 1 of unit 2a has a coupling member 23 soldered or otherwise securely attached to its inner end, and this coupling member slides over the inner end of housing 1 of unit 1a, providing sufficient space between the insulation contact-carrying plate 4 of unit 1a and closure plate 22 to accommodate the movable contact 5 of unit 2a. The coupling member 23 is connected to housing 1 of unit 1a by a structure of the same construction as that employed in connecting the cover cap 19 to the housing 1 of unit 2a.

Each of the units 1a and 2a include a terminal block 28 which, like in the Smith application above-referred to, is slidably carried by the housing 1 of the unit. In the multiple unit attenuator, the terminal blocks 28 are held against longitudinal movement in one direction by contact with the switch panels 4 of the units and by contact with the closure plates 9 and 22 in the other direction, as clearly shown in Figure 2 of the drawings.

By the manner of cutting the shafts 6 and 17 to provide the interengaging semi-cylindrical ends of each shaft, and the provision of the guiding and retaining sleeve 18, the two single units 1a and 2a will and must be in proper synchronized connection for synchronous movement when the shafts are coupled together and when the units are connected to form the single multiple unit device.

It will be understood that the invention is not to be limited to the specific construction or arrangement of parts shown, but that they may be widely modified within the invention defined by the claims.

What is claimed is:

1. In a multiple unit attenuator, a plurality of single units each having an enclosing housing, an annular ring like connecting member rigidly connected to the housing of one of said single units and removably engaging the housing of the other single unit in overlapping engagement, means to prevent accidental displacement of said coupling member and the housing which it detachably engages, terminal blocks slidably carried by said housing, and means to prevent longitudinal movement of the terminal blocks.

2. In a multiple unit attenuator, a plurality of single units each having an enclosing housing, an annular ring like connecting member rigidly connected to the housing of one of said single units and removably engaging the housing of the other single unit in overlapping engagement, means to prevent accidental displacement of said coupling member and the housing which it detachably engages, each of said single units including electrical resistance means including a movable contact unit and an operating shaft for its movable contact unit, said shafts having their inner ends cut away to provide semi-cylindrical inter-engaging coupling sections whereby when the single units are assembled in end to end relation in a multiple unit attenuator the flat surfaces of the shafts of the units will be in flat overlapping engagement for connecting the units for synchronous movement.

3. In a multiple unit attenuator, a plurality of single units each having an enclosing housing, an annular ring like connecting member rigidly connected to the housing of one of said single units and removably engaging the housing of the other single unit in overlapping engagement, means to prevent accidental displacement of said coupling member and the housing which it detachably engages, and each of said single units including electrical resistance means including a movable contact unit and an operating shaft for its movable contact unit, said shafts having their inner ends cut away to provide inter-engaging coupling sections whereby when the single units are assembled in end to end relation in a multiple unit attenuator the flat surfaces of the shafts of the units will be in flat engagement for connecting the units for synchronous movement, and a guiding retaining sleeve about the coupling end of one of said shafts and overlapping the engaging semi-cylindrical coupling portions of the shafts to retain the inner engaging shaft ends in proper engagement.
